CLAIM

The ornamental design for a wall-mounted refrigerator, as shown and described.

DESCRIPTION

1. Wall-mounted refrigerator

1.1 : Perspective

1.2 : Front

1.3 : Back

1.4 : Left

1.5 : Right

1.6 : Top

1.7 : Bottom

1.8 : Reference view showing the state of use

1.9 : Reference view showing the state of use

Broken lines illustrate environmental condition only and form no part of the claimed design.
